UNITED STATES PATENT OFFICE.

SANTINO FALLINI, OF NOVINGER, MISSOURI.

HOG ANTIROOTER.

Application filed October 12, 1925. Serial No. 62,116.

The invention relates to improvements in devices for preventing hogs from rooting or nosing their way under fences and the like, and my object is to provide an exceptionally simple and inexpensive device of this character, yet one which will be very efficient and may be quickly and easily applied.

With the foregoing in view, the invention resides in the novel subject matter hereinafter described and claimed, the description being supplemented by the accompanying drawing.

Figure 1 is a perspective view of the device as manufactured and placed on sale.

Figure 2 is a perspective view showing the manner in which the device is bent after it is applied.

Figure 3 is a perspective view showing the invention in use.

The drawing above briefly described discloses the preferred form of construction, and while such construction is hereinafter specifically described, it is to be understood that variations may be made within the scope of the invention as claimed.

I take a single length of wire of appropriate size and bend it substantially upon itself at its central portion as indicated at 2, providing two substantially parallel arm portions 3. These arm portions are provided with pointed lower ends 4 and constitute prongs adapted to be forced downwardly and forwardly through the upper front portion of a hog's snout. Between their ends, the arm portions 3 are bent to provide stops 5 which limit the extent to which said portions may be passed through the hog's snout, and after said arm portions have been forced downwardly to the extent permitted by these stops, the lower ends of said portions are bent to provide additional stops 6 which prevent withdrawal of the device from the hog's snout. The pointed ends of the wire are then cut off. The bending and cutting operations may be readily accomplished with an ordinary pair of pliers.

In forming the stops 5, I prefer to bend the arm portions 3 horizontally into ring-like form as shown. The stops 6 may be similarly formed.

Preferably, the upper, connected portions of the arms 3 are forwardly bent as indi-

cated at 7, forming a hook which will engage fences or the like if the hog attempts to nose his way beneath the same. The stops 5 and 6, in addition to performing their functions as stops are of course brought into engagement with the earth if the hog attempts to root, and thus, such rooting is prevented.

The device is exceptionally simple and inexpensive, may be easily and cheaply manufactured, and will be highly efficient, as well as being quickly and easily attachable. On account of these good results obtainable from the construction shown, it is preferably followed. However, as above stated, variations may be made.

I claim:

1. A hog anti-rooter comprising a length of wire bent to form substantially parallel arms and a loop, said arms being bent between their ends to form upper stops for engagement with the top of the hog's snout, a forwardly projecting hook on the upper looped ends of said arms formed by outwardly bending said loop, the parts of said arms between said stops and said hook forming an elongated body portion extending upwardly along the top of the hog's face, and lower stops formed on the lower ends of said arms.

2. A hog anti-rooter comprising a length of wire bent to form substantially parallel arms and a loop, said arms being bent midway between their ends to form ring-like upper stops disposed at right angles and transversely to the arms for flat engagement with the top of the hog's snout, a forwardly projecting hook on the upper looped ends of said arms formed by outwardly bending said loop, the parts of said arms between said stops and hook forming an elongated body portion adapted to extend upwardly along the top of the hog's face, and lower stops spaced below said upper stops and adapted to engage the front of the hog's snout.

3. A structure as specified in claim 2; said lower stops being in the shape of rings formed by bending the lower ends of the arms and being disposed at right angles to the arms and in parallel alignment with said upper stops for flat engagement with the front end of the hog's snout.

4. A hog anti-rooter comprising an elongated

gated body portion adapted to extend upwardly along the top of the hog's face, an outwardly projecting hook on the upper end of said body portion, an upper stop on the lower end of said body portion for engagement with the top of the hog's snout, a

per stop, the lower free end of said prong being adapted to be bent to form a lower withdrawal-preventing stop after passage of said prong through the snout.

In testimony whereof I have hereunto affixed my signature.

SANTINO FALLINI.
